UNITED STATES PATENT OFFICE.

JAMES S. PATTEN, OF BALTIMORE, MARYLAND.

THILL-COUPING.

SPECIFICATION forming part of Letters Patent No. 514,493, dated February 13, 1894.

Application filed April 11, 1893. Serial No. 469,925. (No model.)

To all whom it may concern:

Be it known that I, JAMES S. PATTEN, of Baltimore city, in the State of Maryland, have invented a new and useful Improvement in 5 Thill-Couplings, of which the following is a specification.

My invention is an improvement in thill couplings and seeks to provide a simple construction of latch plate and actuating devices 10 whereby the latch may be automatically set and released by the proper movement of the thills and whereby the latch and its actuating devices will operate efficiently to take up all wear and avoid rattling and the invention has 15 for further objects other improvements and consists in the novel constructions and combinations of parts hereinafter described.

In the drawings—Figure 1 is a perspective view. Fig. 2 is a top plan view and Fig. 3 is 20 a side view of my coupling. Fig. 4 is a perspective view of the thill iron with the latch and spring in position for application to the seat. Fig. 5 is a detail view of the latch and Fig. 6 illustrates the manner of automatically 25 setting and releasing the latch.

The clip A is provided with the seat B for the thill iron such seat being preferably formed with the hooks b as shown. The thill iron C is provided with the head to fit the seat B such 30 head having studs D to fit in the hooks b and being provided with lateral lugs d to bear in front of the hooks b as shown.

The latch E is pivoted or hinged at its front edge at e to the thill head such hinge being 35 preferably effected by providing the latch with a stem F which is bent around a central circular portion f of the thill head and permits the pivotal or hinge movement of the latch as desired. At its ends the latch has 40 bearings e' which rest and move snugly against the studs D steadyng the latch in position and preventing any lateral rocking or tilting thereof. Upon the latch at its ends and next to its swinging edge are provided the up- 45 wardly extended lugs or projections e² which serve as abutments to engage the points of the hook in the application of the thill to the seat and cause the free edge of the latch to adjust backward against the spring. At its 50 rear edge the latch is beveled forming an inclined surface which will wedge against the

face of the clip, take up wear and prevent rattling.

A spring G is arranged to actuate the latch and is so connected with the thill that its free 55 end bears upon the latch when the latter is set or in locked position and may move over and into engagement with the swinging edge of the latch to adjust the same to position to remove the thills. To permit the movement of the 60 spring into engagement with the said swinging edge of the latch I provide a way for the spring. This way may be formed by grooving the face of the clip, but it is preferably attained by notching the swinging edge of the latch at e³ 65 so the point or end of the spring may ride past the swinging edge of the latch and between the same and the clip. This spring is secured at one end to the thill and bears at its other or free end upon the latch and is preferably 70 made in two sections G' and G² which may be integral or may be separate and suitably secured together. The section G' presses at its point or free end upon the latch and is secured at its other end to the lower end of section G² the other end of which section is fixed 75 rigidly to the thill the lower end of the section G² being bowed out to give it greater tension. This construction it will be seen permits of greater tension with less spring metal 80 than if a single spring section were used.

In operation when the latch is set and the parts are in the position indicated in dotted lines in Fig. 6, the spring bearing firmly upon the latch will press the same down and cause 85 it to take up the wear, and hold the parts so tightly together as to prevent rattling. If it be desired to remove the thills it is only necessary to lift them until the spring passes the rear edge of the latch when the latter will be 90 thrown into the position shown in full lines Fig. 6 and the thill may then be thrown back to or nearly to a vertical position and lifted from the clips. In applying the thills to the clip the latch being in the position shown in 95 Fig. 4 it will be seen that if the thill head be applied to the clip the lugs on the latch engaging the points of the hooks will cause the latch to tilt back to the position shown in full lines Fig. 6. Now if the thills be lowered 100 from the full line to the dotted line position Fig. 6 the point of the spring will adjust upon

and bear against the top of the latch securing the same set. Thus it will be seen both the application and removal of the thills are entirely automatic, it not being required to handle the latch in either operation.

Having thus described my invention, what I claim as new, and desire to secure by Letters Patent, is—

1. In a thill coupling the combination of the clip having a seat for the thill head, the thill having its head formed to fit said seat, a latch pivoted at one end to the head and movable at its other or free end downward into engagement with the clip, and a spring by which to actuate the latch downward into such engagement substantially as set forth.

2. In a thill coupling the combination of the clip seat the thill having its head fitted to said seat, the latch pivoted at one end and the spring connected at one end with the thill and arranged at its free end to bear upon the latch substantially as set forth.

3. In a thill coupling the thill iron herein described having its head provided with the pivoted or hinged latch provided upon its upper side near its hinged edge with lugs or projections all substantially as set forth.

4. In a thill coupling the thill iron provided with the latch hinged at one edge and provided near said edge with the upwardly extended projections or lugs to engage the points of the clip hooks the iron being provided with lateral shoulders to bear in front of said hooks all substantially as and for the purposes set forth.

5. The combination of the clip having a hook like seat, the thill iron fitted to said seat and provided with lateral shoulders to bear in front of the hook, and the latch hinged at one edge to the thill and provided with the projections or lugs by which to engage the points of the hook substantially as set forth.

6. In a thill coupling the thill iron having a pivoted latch and provided with a spring for actuating the same, said spring being formed in two sections one of which is secured to the thill and the other being secured at one end to the first section and arranged at its other or free end to engage the latch all substantially as set forth.

7. The combination of the clip, the thill, the latch pivoted or hinged at one edge to the thill and a spring arranged to bear at one end upon the said latch a way being provided between the free edge of said latch and the clip whereby the spring may pass said edge substantially as set forth.

8. In a thill coupling the thill iron having its head provided with the latch plate hinged at one edge and provided in its opposite edge with a notch or recess and the spring having its point arranged to bear upon said latch and play through said notch in adjusting from side to side of the latch substantially as set forth.

9. In a thill coupling a thill iron having its head provided with a latch plate hinged at one edge and having its other edge beveled or inclined and the spring by which to actuate said latch plate substantially as set forth.

10. In a thill coupling the combination of the clip having the hook like seat, the thill iron having its head formed to fit said seat and provided with lateral shoulders to bear in front of the hooks the latch hinged at one edge to the thill iron and the spring formed in sections having one section secured to the thill and the other section fixed at one end to said first section and arranged at its other end to bear upon and actuate the latch substantially as set forth.
